US00D916818S

(12) United States Design Patent (10) Patent No.: US D916,818 S
(45) Date of Patent: * Apr. 20, 2021

(54) DISPLAY SCREEN OR PORTION THEREOF
WITH GRAPHICAL USER INTERFACE

D701,225 S * 3/2014 Jung D14/486
D704,220 S 5/2014 Lim et al.
D709,088 S 7/2014 Barchek et al.

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof, and form no part of the claimed design.
